CUTTING TOOL FOR PLASTIC AND THE LIKE

Tony L. Nelms, St. Louis, Mo., assignor to K-S-H, Inc.

Filed July 13, 1971, Ser. No. 162,326

Term of patent 14 years

Int. Cl. D8—03

U.S. Cl. D8—98

FIG. 1.

FIG. 2.

FIG. 3.

FIG. 1 is a view in perspective of a cutting tool for plastic and the like showing my new design;

FIG. 2 is a view in side elevation; and

FIG. 3 is an end view taken along the line 3—3 of FIG. 2.

The two sides of the cutting tool for plastic and the like illustrated are mirror images of one another.

I claim:

The ornamental design for a cutting tool for plastic and the like, as shown and described.
